DESIGN FOR A COMBINATION CLOCK, RADIO, AND LAMP

Abraham I. Shapiro, Boston, Mass.

Application December 26, 1946, Serial No. 135,759

Term of patent 7 years

(Cl. D56—4)

To all whom it may concern:

Be it known that I, Abraham I. Shapiro, a citizen of the United States of America, residing at Boston, in the county of Suffolk and State of Massachusetts, have invented a new, original, and ornamental Design for Combination Clock, Radio and Lamp, of which the following is a specification, reference being had to the accompanying drawings, forming part thereof.

Figure 1 is a perspective view of a combination clock, radio and lamp, embodying my new design.

Figure 2 is a side elevation of the combination clock, radio and lamp shown in Figure 1.

I claim:

The ornamental design for a combination clock, radio, and lamp, as shown.

ABRAHAM I. SHAPIRO.
